UNITED STATES PATENT OFFICE.

JACOB HANDEL, OF NEW YORK, N. Y.

ROTARY VIBRATORY MASSAGE-BRUSH.

No. 866,019.

Specification of Letters Patent.

Patented Sept. 17, 1907.

Application filed October 26, 1906. Serial No. 340,706.

To all whom it may concern:

Be it known that I, JACOB HANDEL, a citizen of the United States, residing in the borough of Manhattan, city, county, and State of New York, have invented 5 certain new and useful Improvements in Rotary Vibratory Massage-Brushes, of which the following is a specification, reference being had therein to the accompanying drawings, in which—

Figure 1 is a side elevation of the apparatus; Fig. 2 10 a longitudinal vertical sectional view of the handle and means for vibrating the brush; Fig. 3 a detail sectional view of a portion of the brush and its holding means; Fig. 4 a detail view showing the means for clamping the brush to the vibratory stock; and Fig. 5 a detail 15 view of the brush.

This invention relates to a vibratory massage device especially designed for cleansing and invigorating the skin and scalp.

The main object of the invention is to provide a 20 vibratory, freely rotatable cylindrical brush, particularly adapted for use in cleansing and invigorating the skin and scalp, wherein the vibrations of the brush will cause it to rotate when it is pressed gently against the surface to be cleaned. The elasticity, or flexibility, 25 of the bristles of the brush and the rapid contacting of the brush with the surface being operated upon will cause the brush to rotate, thus constantly bringing a fresh portion of the brush into action.

I prefer to vibrate the brush by means of an electric 30 motor and suitably connected driving means, whereby the brush will be given very rapid but short vibrations, but it will be understood that I may employ any other suitable means for vibrating the brush.

Referring to the various parts by numerals, 1 designates an electric motor; 2 a flexible shaft connected thereto and driven thereby. On the end of this shaft is secured a non-rotating handle 3, within which is mounted a rigid shaft 4 said shaft being connected to the flexible shaft and driven thereby. The handle is 40 provided with a head 5, at its outer end, which is arranged transversely of the handle and is provided with a vibrating stock 6. This stock is formed with a socket 7 in which rotates a cam 8 by which the stock is given a very rapid movement in the head 5 of the handle. 45 The stock 6 is formed with a socket 9 to receive the stem 10 of the brush supporting yoke 11. To secure this stem in place a split tapered locking sleeve 12 is provided which is adapted to be screwed up into the stock 6 around the stem 10.

50 A brush 13 is mounted in the yoke 11. The brush body is formed with apertures 14 in which the journal studs 15 are loosely mounted. These studs are threaded to receive the screw 16 which extends through the yoke 11, as shown clearly in Fig. 3. The brush is 55 freely rotatable on the studs 15. It will be noted that the movement of vibration of the brush is perpendicu-

lar to the axis of the brush so that it is moved toward and from the surface to be treated.

In use the brush is placed against the surface to be treated and the rapid vibrations imparted to said brush 60 by means of the cam 8, cause the bristles to be flexed slightly as shown in Fig. 5, and as the brush is withdrawn from the surface to be treated by the cam 8 the bristles in straightening impart a rotary movement to the brush, thereby presenting a fresh part to the surface being operated upon. The rapid vibrations of the brush alone will cause the brush to rotate on its axis and the tendency to rotate is increased when the brush is brought against a surface to be cleaned with a slight pressure. This is of great advantage when massaging 70 faces as a fresh portion of the brush will be presented to the skin and the brush will have a wiping action instead of merely pounding the flesh, as is the case with massage devices commonly employed.

It will, of course, be understood, that I may use 75 brushes of various sizes having bristles of various degrees of flexibility. For treating the face and body brushes having very fine bristles will be used, while in treating the scalp, heavier and stiffer brushes will be employed.

Having thus described my invention, what I claim 80 as new and desire to secure by Letters Patent, is:—

1. A brushing or massage apparatus comprising a motor, a flexible shaft connected thereto, a non-rotatable handle secured to the end of said shaft, a vibratory stock 85 carried by said handle, means connecting the flexible shaft to said stock to vibrate the same, a yoke, means for detachably connecting the yoke to the stock, a freely rotatable cylindrical brush mounted in said yoke, the axis of said brush being perpendicular to the movement of the vibratory stock, said brush being formed of substantially radial, flexible bristles, whereby when the brush is placed against a surface the vibrations of the brush will alternately flex the bristles and then permit them to straighten and thereby rotate the brush in its bearings. 90

2. A brushing or massage apparatus comprising a motor, a flexible shaft connected thereto, a non-rotatable handle carried by said shaft, a vibratory stock within said handle, means for connecting the flexible shaft to said stock to rapidly vibrate the same by imparting to it a reciprocating motion, a yoke provided with a stem midway its ends means for detachably connecting said stem to the vibratory stock, a pair of inward extending rigid bearing pintles secured to the ends of the yoke, a freely rotatable cylindrical brush mounted on said pintles and formed with substantially radial flexible bristles, the axis of said brush being perpendicular to the reciprocating movements of the stock, whereby the rapid impact of the brush against a surface will alternately flex the bristles and then permit them to straighten out to rapidly rotate 100 the brush. 105

In testimony whereof I hereunto affix my signature in the presence of two witnesses this 25th day of October 1906.

JACOB HANDEL.
